Sec. 902

Samuel D. Nose, of Albany, N. Y.
Letters Patent No. 902. Dated July 7th 1857.

The schedule referred to in these Letters Patent, and making part of the same.

To all whom it may concern:

Be it known that I, Sam'l. D. Nose, of Albany, County of Albany and State of New York, have invented or produced a new design for ornamenting stoves, and I do hereby declare that the following is a full and exact description of the same, reference being had to the drawing annexed to and making part of this specification.

The nature of my invention will not admit of an intelligible description in words, being made up of a combination of mouldings and figures, as shown in the accompanying diagram.

The drawing Fig: 1, represents the new design I have produced and is a fac-simile of my invention.

I do not claim any separate moulding or figure in the configuration. What I claim as my invention & desire to secure by letters patent is the arrangement & combination of the various figures & mouldings, the whole forming an ornamental design for stoves, as herein described.
